UNITED STATES PATENT OFFICE

2,534,937

GRINDING MACHINE

Wallace H. Wood, Worcester, Mass., assignor to
 Norton Company, Worcester, Mass., a corpora-
 tion of Massachusetts

Application November 28, 1947, Serial No. 788,725

13 Claims. (Cl. 51—233)

1

The invention relates to a grinding machine and more particularly to a hydraulically operated grinding machine.

One object of the invention is to provide a simple and thoroughly practical hydraulically operated grinding machine. Another object is to provide an improved hydraulic table reciprocating mechanism.

Another object is to provide a table-actuated pilot valve and a reversing valve which are simultaneously shifted by table movement until exhaust of fluid is cut off from table cylinder to stop the table, after which the pilot valve directs fluid under pressure through a throttle valve into an end chamber in the reversing valve to shift the reversing valve at a slow rate (dwell) and a by-pass port opened thereafter to admit fluid under pressure rapidly to snap the reverse valve into a reverse position.

Another object of the invention is to provide means actuated by the feed control valve automatically to bleed the pressure end of the table cylinder thereby eliminating air which may leak into the system.

Another object is to provide a hydraulic vane-type motor to feed the grinding wheel and a control valve therefor which is actuated by and in timed relation with the table reverse valve so as to produce an infeed during table reversal. Another object is to provide a slidable sleeve for the feed control valve which automatically resets the timing of the valve ahead of the dead center for the reverse stroke so that an infeed of the grinding wheel is completed before the table starts its traverse in the opposite direction.

Another object is to provide a direct by-pass to pass fluid under pressure directly from the pump (pressure line) to the reservoir when the machine is idle thereby eliminating wire-drawing of the fluid and the resultant heating of the fluid.

A further object is to provide a start and stop valve which is arranged when shifted to a start position to actuate a cam mechanism to disengage clutch to render hand traverse mechanism inoperative and to open a V-port so as to start reciprocation of the table.

A further object is to provide a start and stop valve which is arranged when shifted to a stop position (1) to close a V-port to stop table reciprocation, (2) cam recedes to render hand traverse mechanism operative, (3) opens by-pass between opposite ends of table cylinder to facilitate manual operation of table, and (4) open by-pass to pass fluid under pressure directly from the pump to the reservoir.

2

Other objects will be in part obvious or in part pointed out hereinafter.

This invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a fragmentary front elevation of the improved grinding machine;

Fig. 2 is a fragmentary cross sectional view through the grinding machine, taken approximately on the line 2—2 of Fig. 1, showing the wheel feeding mechanism;

Fig. 3 is a vertical sectional view, on an enlarged scale, taken approximately on the line 3—3 of Fig. 1, through the hydraulic wheel feed motor;

Fig. 4 is a vertical sectional view, taken approximately on the line 4—4, through the hydraulic feed motor;

Fig. 5 is a fragmentary vertical sectional view, taken approximately on the line 5—5 of Fig. 3;

Fig. 6 is a vertical sectional view, on an enlarged scale, taken approximately on the line 6—6 of Fig. 1, through the actuating mechanism for the table pilot and reversing valves;

Fig. 7 is a fragmentary front elevation of the actuating mechanism for the table pilot and reversing valves;

Fig. 8 is a vertical sectional view, on an enlarged scale, taken approximately on the line 8—8 of Fig. 1, through the start-stop and speed control lever and valve;

Fig. 9 is a horizontal sectional view, on an enlarged scale, taken approximately on the line 9—9 of Fig. 8, through the pilot and reversing valves;

Fig. 10 is a fragmentary plan view, on an enlarged scale, of the hydraulic table cylinder and the control valve unit therefor;

Fig. 11 is a vertical sectional view, taken approximately on the line 11—11 of Fig. 10, showing the table cylinder and control valve unit in elevation;

Fig. 12 is a fragmentary plan view, on an enlarged scale, of the manually operable table traverse mechanism;

Fig. 13 is a horizontal sectional view, on an enlarged scale, taken approximately on the line 13—13 of Fig. 1, through the manually operable table traverse mechanism;

Fig. 14 is a diagrammatic illustration of the

hydraulic control mechanism and the piping therefor;

Fig. 15 is a fragmentary vertical sectional view, on an enlarged scale, through the wheel feed motor control valve;

Fig. 16 is a horizontal sectional view, taken approximately on the line 16—16 of Fig. 15, through the wheel feed motor control valve; and

Fig. 17 is a plan view of the table reversing valve sleeve, on an enlarged scale, showing the ports.

An improved hydraulically operated grinding machine has been illustrated in the drawings comprising a base 10 which serves as a support for a longitudinally reciprocable work supporting table 11. The table 11 is arranged to be traversed or reciprocated longitudinally on a flat way 12 and a V-way 13 formed on the upper surface of the base 10.

The table 11 serves as a support for a headstock 14 having a headstock center 15 and a footstock 16 having a footstock center 17 rotatably to support opposite ends of a work piece to be ground. An electric motor 18 is mounted on the headstock 14 to drive the work.

The base 10 also serves as a support for a transversely movable wheel slide 21 which is arranged to slide transversely on the usual ways (not shown) on a wheel slide base 22. The wheel slide 21 is provided on its upper surface with a cylindrical aperture 23 which mates with a correspondingly shaped surface formed on the under side of a swivel head 24. The swivel head 24 serves as a support for a transversely adjustable wheel head 25 which supports a rotatable grinding wheel 20. A clamping bolt 26 is provided for locking the wheel head 25 in adjusted position on the swivel head 24. It will be readily apparent from the foregoing disclosure that the swivel head 24 may be angularly adjusted relative to the wheel slide 21 and the wheel head 25 may be adjusted transversely relative to the swivel head 24 to facilitate setting-up the machine.

In order to provide an angular feeding movement of the wheel slide 21, the wheel slide base 22 is provided with a downwardly projecting cylindrical surface 27 which mates with a correspondingly shaped aperture formed in the upper surface of a base plate 28. The wheel slide base 22 may be clamped in adjusted angular position on the base plate 28 by means of clamping bolts (not shown) which ride in a circular T-slot formed in the upper surface of the base plate 28 (Fig. 2).

The grinding wheel 20 is driven by an electric motor 30 which is mounted on the upper surface of the wheel head 25. A motor shaft 31 is connected by driving belts (not shown) with the grinding wheel spindle to rotate the grinding wheel 20. The driving belts are contained within a belt guard 32 (Fig. 1).

A suitable feeding mechanism is provided for feeding the wheel slide 21 transversely toward and from the work piece being ground. This mechanism may comprise a rotatable feed screw 35 which is rotatably supported by anti-friction bearings 36 and 37 carried by the wheel slide base 22. A half nut 38 depends from the under side of the wheel slide 21 and mates with the feed screw 35. In order to rotate the feed screw 35, a bevel gear 39 is keyed on the feed screw shaft (Fig. 2). The bevel gear 39 meshes with a bevel gear 40 which is mounted on the upper end of a vertically arranged rotatable shaft 41. In order to impart a feeding movement to the wheel slide

21 in any angular position of the wheel slide base 22, the shaft 41 is arranged with its axis coinciding with the axis of the cylindrical surface 27. A bevel gear 42 is mounted on the lower end of the shaft 41. The bevel gear 42 meshes with a bevel gear 43 which is journaled in anti-friction bearings 44 and 45. The bearings 44 and 45 are fixedly mounted relative to the base 10. A rotatable shaft 46 is slidably keyed to the bevel gear 43. A manually operable feed wheel 47 is mounted on the forward end of the shaft 46. It will be readily apparent from the foregoing disclosure that a manual rotation of the hand wheel 47 is transmitted to impart a transverse feeding movement to the wheel slide 21 and the grinding wheel 20.

A manually operable traverse mechanism is provided for imparting a longitudinal traversing movement to the table 11. A hand traverse apron 50 is mounted on the front of the base 10 (Figs. 1, 12 and 13). A rotatable shaft 51 is journaled in anti-friction bearings 52 and 53 which are supported in the apron 50 (Figs. 12 and 13). The shaft 51 supports a bushing 54 which in turn supports a rotatable sleeve 55. A hand traverse wheel 56 is keyed on the forward end of the sleeve 55. A gear 57 is formed integral with the sleeve 55 and meshes with a gear 58. The gear 58 is supported by a bushing 59 which is rotatably mounted on a shaft 60. The shaft 60 is supported by anti-friction bearings 61 and 62 which are supported in the apron 50. A gear 63 is formed integral with the gear 58 and is meshed with a gear 64 which is keyed on the shaft 51. A gear 65 fixedly mounted on the shaft 51 meshes with a gear 66. The gear 66 is rotatably mounted on the shaft 60. A clutch member 67 is slidably keyed on a bushing which is fixedly mounted on the shaft 60. A set of clutch teeth 68 on the clutch member 67 are arranged to engage a set of clutch teeth 69 formed integral with the gear 63 when the clutch member 67 is moved toward the front of the machine. A set of clutch teeth 70 are arranged to engage a set of clutch teeth 71 formed integral with the gear 66 when the clutch member 67 is moved toward the rear of the machine.

A gear 72 is rotatably mounted on the shaft 60 and meshes with a rack bar 73 depending from the under side of the table 11. A clutch member 74 is slidably keyed on a sleeve which is fixedly mounted on the shaft 60. The clutch member 74 is provided with clutch teeth 75 which are arranged to engage clutch teeth 76 formed integral with the gear 72 when the clutch member is moved toward the front of the machine. When clutch teeth 75 and 76 are engaged, a rotary motion of the shaft 60 is imparted to the gear 72 to traverse the rack bar 73 and work table 11 longitudinally.

The clutch member 74 is arranged to be actuated by a bell crank lever 80 which is pivotally supported on a stud 81 (Figs. 12 and 13). The horizontal arm of the bell crank lever 80 is provided with a stud 82 which rides in a groove 83 formed in clutch member 74. A compression spring 84 surrounding a stud 85 engages the horizontal arm of the bell crank lever 80 and serves normally to maintain the clutch member 74 engaged. A slidably mounted rod 86 is arranged when moved toward the left (Figs. 12 and 13) to rock the bell crank lever 80 in a clockwise direction to disengage the clutch member 74 against the compression of the spring 84. The rod 86 is arranged to be actuated automatically in a manner to be hereinafter described by means of a slidably mounted rod 87 (Fig. 11) which is actu-

ated by a frusto-conically shaped cam 88 (Fig. 8). The rods 86 and 87 are arranged in axial alignment with each other. An adjusting screw 89 and a lock nut 90 are mounted in the left hand end of the rod 87 to facilitate taking up lost motion between the rods 86 and 87.

The clutch 67 is actuated by means of a rock arm 93 which is pivotally supported by a stud 94. The arm 93 carries a stud 95 which rides in a groove 96 formed in the clutch member 67. The left hand end of the rock arm 93 is operatively connected to a slide rod 97 which projects from the front of the machine base 10. An actuating knob 98 is mounted on the outer end of the rod 97 to facilitate actuation of the clutch member 67.

The manually operable table traverse mechanism is preferably arranged so that either a rapid or a slow manual traversing movement of the table 11 may be obtained by manipulation of the clutch member 67. In order to obtain a rapid manual traverse of the table 11, the knob 98 is pulled out so as to slide the clutch member 67 forward to engage the clutch teeth 68 with the clutch teeth 69. In this position of the clutch 67, rotation of the hand wheel 56 will be transmitted through the sleeve 55, the gear 57, the gear 58, through the clutch member 67 to rotate the shaft 60. Rotation of the shaft 60 is transmitted through the clutch member 74 to rotate the gear 72 and through the rack bar 73 to traverse the table 11 longitudinally.

In order to obtain a slow manual traverse, the knob 98 is pushed in so as to slide the clutch member 67 rearwardly to engage the clutch teeth 70 with the clutch teeth 71. In this position of the clutch 67, rotation of the hand wheel 56 is transmitted through the sleeve 55, the gear 57, the gear 58, the gear 63, the gear 64, the shaft 51, the gear 65, the gear 66 and the clutch member 67 to rotate the shaft 60 and thereby to transmit a slow manual traversing movement to the table 11. The ratio of the high and the low speed gear drive for the hand traverse mechanism is 10 to 1.

Due to the gear ratio, rotation of the hand wheel 56 to produce a 10 thousandths ($\frac{1}{100}$) of an inch adjustment of the table 11 when clutch member 67 is in low gear, will result in a 10 hundredths ($\frac{1}{10}$) of an inch adjustment if the clutch member 67 is shifted into high gear.

In order to facilitate a precise manual traversing movement of the table 11 for a shoulder grinding operation and the like, a graduated dial 99 is provided. The dial 99 is rotatably supported on the sleeve 55 so that it may be readily adjusted relative to the hand traverse wheel 56 to facilitate setting the zero point of the scale in setting up the machine for a grinding operation requiring a manual traversing or positioning of the table 11. A clamping screw 99a is provided for locking the dial 99 in adjusted position relative to the hand wheel 56.

The table 11 is reciprocated longitudinally by means of a hydraulically operated mechanism comprising a cylinder 100 (Fig. 14) which contains a slidably mounted piston 101. The cylinder 100 is fixedly mounted on the base 10. The piston 101 is connected to a double end piston rod 102, the opposite ends of which are connected to the table 11.

A suitable control valve mechanism is provided whereby the table 11 may be readily started and stopped when desired. A table actuated pilot and reversing valve mechanism are provided for controlling the admission to and exhaust of fluid

from the table cylinder 100. A control apron 103 is mounted on the front of the machine base 10 (Figs. 1, 6, and 8). A control valve unit 104 is supported by a bracket 105 which surrounds the cylinder 100 (Figs. 6, 8, 10 and 11). The control valve unit 104 contains a reversing valve 106, a pilot valve 107, and a start-stop valve 108 (Figs. 6, 8, 9, 10 and 11). In the hydraulic diagram (Fig. 14), these valves have been diagrammatically separated to clarify the hydraulic connections and operation thereof.

The reversing valve 106 is a piston-type valve comprising a valve stem 109 having valve pistons 110, 111 and 112 formed integrally therewith. An actuating spool 113 is mounted on the end of the valve stem 109.

The pilot valve 107 is similarly a piston-type valve comprising a valve stem 115 having valve pistons 116, 117, 118, and 119 formed integrally therewith. An actuating spool 120 is mounted on the end of the valve stem 115. The pilot valve 107 is normally held in a central position by means of a balanced spring mechanism comprising a pair of flanged sleeves 121 and 122 which are slidably mounted on the opposite ends of the valve stem 115. Balanced compression springs 123 and 124 surround the sleeves 121 and 122 respectively and are interposed between flanges on sleeves 121 and 123 respectively and fixed collars on the valve stem 115. The springs 123 and 124 serve normally to maintain the pilot valve 107 in the position shown in Figs. 9 and 14.

The start-stop valve 108 is a piston-type valve comprising a valve stem 125 having valve pistons 127, 128 and 129 formed integrally therewith. A V-port 130 is formed in the valve piston 128 which is arranged when the valve 108 is in a start position to control the exhaust of fluid from the cylinder 100 and thereby to control the speed of movement of the table 11. A serrated portion 131 on the valve stem 125 is engaged by a spring-pressed detent 132 supported by the casing of the valve 108. The serrated portion 131 and detent 132 serve to maintain the valve stem 125 and V-port 130 in the desired rotary adjusted position during axial movement of the stem 125 when shifted to start and stop positions so as to facilitate starting and stopping the table 11 without disturbing the adjustment 50 of the V-port 130.

A spool-shaped member 133 is connected by a stud 134 with a pivotally mounted Start-Stop lever 135. The lever 135 is supported by a stud 136 which is in turn fixedly mounted on the front of the apron 103. A knob 137 is mounted on the outer end of the valve stem 125 to facilitate a rotary adjustment of the V-port 130 so as to regulate the speed of the table 11.

A hydraulic system is provided for supplying fluid under pressure to the various mechanisms of the machine. This system comprises a motor driven fluid pump 140 which draws fluid through a pipe 141 from a reservoir 142. The pump 140 forces fluid under pressure through a pipe 143 which conveys fluid under pressure to the table reciprocating and wheel feeding mechanisms. An adjustable pressure relief valve 144 is connected in the pipe 143 by means of which excess fluid under pressure may be-pass directly 70 to the reservoir 142. By adjustment of the relief valve 144, the desired operating pressure may be maintained within the system.

Assuming the Start-Stop lever to be shifted in a counterclockwise direction to a start position, 75 fluid under pressure in the pipe 143 enters a

valve chamber located between the valve pistons 111 and 112 of the reversing valve 106 and passes out through a pipe 145 into a cylinder chamber 146 at the right hand end of the cylinder 100. Fluid under pressure entering cylinder chamber 146 causes the piston 101 and table 11 to move toward the left. During this movement of the table 11, fluid within a cylinder chamber 147 exhausts through a pipe 148 into a valve chamber located between the valve pistons 110 and 111 and passes out through a pipe 150, through the V-port 130 in the Start-Stop valve 108 and through an exhaust pipe 151 into the reservoir 142. The speed of movement of the piston 101 and the table 11 may be adjusted by a rotary adjustment of the knob 137 and the V-port 130.

The pilot valve 107 is arranged to control the admission to and exhaust of fluid from end chambers 158 and 162 formed in opposite ends of the reversing valve 106. Fluid under pressure in the pipe 148 is admitted at all times to a valve chamber 155 located between the valve pistons 117 and 118 of the pilot valve 107.

When the pilot valve stem 115 is shifted toward the right (Fig. 14), a port is uncovered to pass fluid under pressure from the valve chamber 155 through a passage 156, through a throttle valve 157 into the end chamber 158 of the reversing valve to shift the valve stem 109 toward the left at a slow rate until a relatively large port 159 is uncovered by valve piston 112 to allow fluid under pressure to by-pass the throttle valve 157 and to pass in a relatively large volume into the end chamber 158 to snap the reversing valve rapidly into a reverse position. This movement of the reversing valve 106 serves to pass fluid under pressure through the pipe 148 into cylinder chamber 147 to start movement of the piston 101 and table 11 toward the right.

During the shifting of reverse valve stem 109 toward the left, fluid within the end chamber 162 is free to exhaust through a pipe 165 into a valve chamber 166 and out through an exhaust pipe 167 into the reservoir 142.

When the pilot valve stem 115 is shifted toward the left (Fig. 14), a port is uncovered to pass fluid under pressure from the valve chamber 155 through a passage 160, through a throttle valve 161 into the end chamber 162 to shift the valve stem 109 toward the right at a slow rate until a relatively large port 168 is uncovered by valve piston 110 to allow fluid under pressure to by-pass the throttle valve 161 and to pass in a relatively large volume into the end chamber 162 to snap the reversing valve rapidly into a reverse position. This movement serves to position the reversing valve 106 in the position illustrated in Fig. 14.

A manually operable reversing lever 170 is mounted on the front end of a rock shaft 171 which is rotatably mounted in the apron 103. A sleeve 172 is keyed on the inner end of the rock shaft 171. The sleeve 172 is provided with an integral upwardly extending arm 173 which is connected by a stud 174 with the spool 113, on reverse valve stem 108. The sleeve 172 is also connected in a manner to be hereinafter described to the spool 120 on the pilot valve stem 115. A manual actuation of the lever 170 serves to shift reversing valve 106 and pilot valve 107 manually to reverse the direction of movement of piston 101 and table 11.

It is desirable to provide a suitable table actuated mechanism for automatically actuating the reversing valve 106 and the pilot valve 107. A reversing lever 175 is vertically slidable on a

plate 176. A compression spring 177 serves normally to maintain the lever 175 in an uppermost position in the path of a pair of adjustable table dogs 178 and 179 (Figs. 1 and 7). The dogs 178 and 179 are adjustably supported by bolts which slide in a T-slot formed in the front edge of the table 11. The plate 176 is formed integral with a rock shaft 180 which is supported in a bearing 181 in the apron 103. A downwardly extending rock arm 182 is keyed to the inner end of the rock shaft 180. The rock arm 182 is provided at its lower end with a stud 183 which rides in the spool 120 on the pilot valve stem 115. A rock arm 184 (Figs. 6 and 7) is rotatably supported on the rock shaft 180. A gear segment 185 is formed on the lower end of the arm 184 which meshes with an idler gear 186. The gear 186 is rotatably supported on a stud 187. The gear 186 meshes with a gear 188 which is formed integral with the sleeve 172.

A lost motion connection is provided between the rock arm 182 and the rock arm 184. The rock arm 182 is provided with oppositely extending lugs 190 and 191 which are provided with adjusting screws 192 and 193 respectively. The adjusting screws 192 and 193 are arranged in the path of a pair of rearwardly extending lugs 194 and 195 formed integral with the rock arm 184. The lost motion connection is provided so that after the reverse valve 106 has been shifted into a reverse position, the released compression of the spring 123 or 124 may return the pilot valve 107 to a central position as shown in Fig. 14.

It will be readily apparent from the foregoing disclosure that either the table dog 178 or the dog 179 engages the reversing lever 175 to initiate a reversal of the table, the initial movement of the reverse lever 175 serves simultaneously to shift both reversing valve 106 and pilot valve 107 by movement of the table 11. This movement of the valves continues until the valve piston 111 cuts off exhaust of fluid from the cylinder 100 to stop the movement of the table 11. When the reverse valve 106 is in this position, the pilot valve stem 115 has moved a sufficient distance so that fluid under pressure in the valve chamber 155 may pass through either passage 156 or 160 to cause a slow shifting movement of the reversing valve until the port 159 or 168 is opened to snap the reversing valve rapidly and positively into a reverse position by means of fluid under pressure.

The relatively slow movement of the reversing valve 106 as governed by throttle valves 157 and 161 serves to provide a tarry or dwell at the ends of the table stroke during the period of reversal. By adjustment of the throttle valves 157 and 161, the period of dwell at either or both ends of the table stroke may be adjusted as desired. To facilitate adjustment of throttle valves 157 and 161, adjusting knobs 198 and 199 are provided on the front of the machine (Figs. 1, 8 and 10).

A hydraulically operated feeding mechanism is provided for automatically producing an infeeding movement of the grinding wheel 20 during the dwell period at the ends of the reciprocatory stroke of the table 11. This mechanism preferably comprises a single vane-type fluid motor 200 having a rotor shaft 201 which supports a rotor 202 (Figs. 3, 4 and 14). A single vane 203 is fixedly mounted on the rotor 202 which is arranged to rotate less than 360° within a motor chamber 204. An arcuate shaped block 205 having end stop surfaces 206 and 207 serves to limit the oscillating stroke of the vane 203. The rotor

shaft 201 projects from the front of the machine base and is provided on its outer end with a plate 208 having a radially extending T-slot (Figs. 1 and 3) which supports an adjustable stud 209. The stud 209 may be adjusted relative to the plate 208 so that it is either concentric with or eccentric relative to the axis of the rotor shaft 201.

In order to transmit a feeding movement to the feed screw 35, a yoke 210 straddles the stud 209. The yoke 210 is formed integral with a rock arm 211 which is arranged to oscillate about the axis of the shaft 46. An arm 212 is formed integral with the arm 211 so as to form a bell-crank lever. The arm 212 carries a stud 213 which serves as a support for a pawl arm 214. The pawl arm 214 is provided with a stud 215 which supports a small gear 216. The gear 216 serves as a feed pawl and meshes with a gear 217 mounted on the feed shaft 46. A ball clutch (not shown) is interposed between the small gear 216 and its supporting stud 215. The ball clutch is arranged so that the gear 216 rolls idly over the teeth of the gear 217 during an upward movement of the pawl arm 214. During downward movement of the pawl arm 214, the ball clutch locks the gear 216 to the pawl arm 214 and thereby imparts a rotary motion to the gear 217. During each oscillation of the motor vane 203, the eccentric stud 209 imparts a down and an up stroke to the pawl arm 214 and gear 216 so as to impart an infeeding movement to the grinding wheel 20 at each end of the reciprocatory stroke of the table 11. This feeding movement continues until the upper end of the pawl arm 214 is engaged by a stop abutment 218 carried by the feed wheel 47 which stops the infeeding movement of the grinding wheel 20 when the work piece being ground has reached a predetermined size. It will be readily apparent from the foregoing disclosure that the extent of each feeding movement may be adjusted by varying the eccentricity of the stud 209.

A reversing valve 220 (Figs. 4, 14 and 15) is provided for controlling the admission to and exhaust of fluid from the wheel feed motor 200. The valve 220 is a piston type valve comprising a valve stem 221 having valve pistons 222, 223 and 224 formed integrally therewith. The fluid pressure pipe 143 is connected to a control valve 225 which is actuated by a knob 226 to control the admission of fluid under pressure through a passage 227 to ports 228 and 229 in the reversing valve 220 to control the starting-stopping and speed of movement of the motor vane 203. In the position of valve 220 (Figs. 4, 14, and 15), fluid under pressure enters through the port 228 into a valve chamber formed between the valve pistons 223 and 224 and passes through a passage 231 into a motor chamber 232 to cause the motor vane 203 to revolve in a clockwise direction. During this movement of the motor vane 203, fluid within motor chamber 233 is forced out through a passage 234 into a valve chamber formed between the valve pistons 222 and 223. Fluid exhausting into the latter chamber passes out through an exhaust port 236 and an exhaust pipe 237 to the reservoir 142.

The motor vane 203 continues its clockwise or counterclockwise movement until it engages a stop face 206 or a stop face 207 on the block. The pressure remains on the operative side to hold the vane 203 against the stop face until the control valve 220 is again shifted thereby preventing movement of the feed pawl 214.

It is desirable that the valve 220 be actuated in timed relation with the table reciprocation so

that the infeed of the grinding wheel may be obtained at the end of the table stroke during the period of reversal. In the preferred construction, the control valve 220 is actuated in timed relation with the actuation of the table reversing valve 106. The valve stem 221 is connected by a stud 238 with a link 239. The other end of the link 239 is connected by a stud 240 with the arm 173 which actuates the reversing valve 106 (Figs. 4, 6 and 14). It will be readily apparent from the foregoing disclosure that the valve 220 will be actuated by and in timed relation with the table reversing valve 106.

It is also desirable that the infeeding movement of the grinding wheel 20 be completed during table reversal before the table 11 starts moving in the opposite direction. This is preferably accomplished by constructing the valve 220 so that the timing of the valve is reset ahead of dead center for the reverse stroke. As illustrated in Figs. 4, 14, 15 and 16, a sliding valve sleeve 241 surrounds the valve pistons 222, 223 and 224. The sleeve 241 is slightly longer than the surrounding motor casing and is arranged to be moved in an axial direction either by means of a shoulder on the valve stem 221 at one end or a collar 243 at the other end. The sleeve 241 is provided with a plurality of ports 228a, 229a, 230a, 235a, and 236a which correspond with the spacing of the ports 228, 229, 230, 235 and 236 in the casing. The ports 228a, 229a, 230a, 235a, and 236a in the sleeve 241 are enlarged adjacent to the periphery of the sleeve 241 so that in any position of the sleeve 241, they are in full communication with the ports 228, 229, 230, 235 and 236. The sleeve 241 is arranged so that it has an axial stroke of approximately $\frac{1}{8}$ of an inch relative to the case. A friction plunger 242 mounted in the casing frictionally engages a plane surface 244 formed on the sleeve 241 to maintain the sleeve against movement except when moved by the stem 221.

When the valve stem 221 is moved toward the left (Fig. 15) by actuation of the reversing valve 106 (Fig. 14), the valve pistons 222, 223 and 224 slide within the sleeve 241 until the collar 243 engages the end of the sleeve 241 and continued movement of the valve stem 221 then slides the sleeve 241 toward the left to reset the ports 228a, 229a, 230a, 235a and 236a. The resetting of the sleeve 241 serves to advance the position of the ports 228a, 229a, 230a, 235a and 236a and thereby to advance the picker feed function so that it completes an infeeding movement of the grinding wheel during the dwell provided at table reversal before the table 11 starts moving in the reverse direction. The sleeve 241 functions in a similar manner when the valve stem 221 is shifted toward the right.

To eliminate air from the hydraulic system, it is desirable to provide suitable means for automatically bleeding the system during operation of the machine. A pair of bleeder pipes 250 and 251 are connected to opposite ends of the table cylinder 100 (Fig. 14). The bleeder pipes 250 and 251 are connected to the feed control valve 220 so that the pressure side of the cylinder is automatically vented. The sleeve 241 is provided on its outer periphery with a pair of slabbed portions which form a pair of valve chambers 253 and 255. In the position shown in Figs. 14 and 15, fluid bleeding through pipe 250 passes through a port 252 and through the valve chamber 253 and drains into the reservoir 142. When reversing valve 106 and valve 220 are in reverse posi-

tions so that fluid under pressure is supplied to cylinder chamber 147, fluid bleeds from cylinder chamber 147, through the bleeder pipe 251, through a port 254 and the valve chamber 255 into the reservoir 142. It will be readily apparent from the foregoing disclosure that the pressure side of the table cylinder 100 is continuously vented to bleed any air which may leak into the system into the reservoir.

The operation of the improved grinding machine will be readily apparent from the foregoing disclosure. Assuming all adjustments to have previously been made, the work drive motor 18, the wheel drive motor 30 and the fluid pump motor are started. A work piece to be ground is mounted on headstock center 15 and footstock center 17 with the work piece being driven in the conventional manner, namely, by means of a work driving dog. The Start-Stop lever 135 is moved in a counterclockwise direction (Figs. 8 and 14) to open the V-port 130 which allows fluid to exhaust from the cylinder chamber 147 thereby starting reciprocation of the table 11. The table dogs 178 and 179 actuating the reverse lever 175 serve to reverse the table movement in a manner above described at the ends of the predetermined stroke. Through actuation of the feed control valve 220, the grinding wheel 20 is automatically fed into the work piece being ground during the dwell at reversal at each end of the table stroke. The infeeding movement of the grinding wheel continues intermittently at the ends of the table stroke until the stop abutment 218 on the feed wheel 47 engages the end of the pawl arm 214.

When it is desired to stop the operation of the machine, the lever 135 is moved in a clockwise direction into the position illustrated in Fig. 14, to close the V-port 130 thereby cutting off the exhaust of fluid from the cylinder 100 to stop the reciprocation of the table 11. When the valve 108 is moved to a stopped position, the cam 88 recedes so that the released compression of the spring 84 engages the clutch member 74 to render the manually operable traverse wheel 56 operative. In this position of the valve 108 fluid may by-pass directly between cylinder chambers 146 and 147 to facilitate manual traverse of the table 11. Fluid also by-passes directly from the pressure pipe 143 into the reservoir 142 thus preventing wire-drawing of the pressure fluid and resultant excessive heating of the fluid.

It will thus be seen that there has been provided by this invention apparatus in which the various objects hereinabove set forth together with many thoroughly practical advantages are successfully achieved. As various possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine having a longitudinally reciprocable table, a piston and cylinder to reciprocate said table, a reversing valve therefor, an end chamber in each end of said valve, a pilot valve, a stop and start valve to control the exhaust of fluid from said cylinder to start and stop table reciprocation, a table-actuated lever which is operatively connected to shift both the pilot and reversing valves to stop the table, fluid connections between each of the end chambers and the pilot valve positively to shift the

reversing valve slowly, a throttle valve in each of said connections to regulate said slow movement of the reversing valve in either direction to provide a predetermined table dwell at reversal, and separate ports in the reversing valve which are opened after a predetermined slow movement to by-pass fluid around the throttle valves into the end chambers rapidly to shift the reversing valve into its reverse position.

2. In a grinding machine having a longitudinally reciprocable table, a piston and cylinder to reciprocate said table, a reversing valve therefor, an end chamber in each end of said valve, a pilot valve, a stop and start valve to control the exhaust of fluid from said cylinder, a table actuated lever which is operatively connected to shift both the pilot and reversing valves to stop the table, fluid connections between each of the end chambers and the pilot valve positively to shift the reversing valve slowly, a throttle valve in each of said connections to regulate said slow movement of the reversing valve in either direction, separate ports in the reversing valve which are opened after a predetermined slow movement to by-pass fluid around the throttle valves into the end chambers rapidly to shift the reversing valve into its reverse position, and separate passages between the end chambers and the pilot valve which are arranged to facilitate unrestricted exhaust of fluid from the inactive end chamber.

3. In a grinding machine having a reciprocable work table, a piston and cylinder to reciprocate said table, a reversing valve therefor, end chambers in opposite ends of said valve to facilitate fluid pressure actuation of the valve, a pilot valve for controlling the shifting of the reversing valve, a start and stop valve to control exhaust of fluid from said cylinder, a table-actuated lever mechanism to shift both the pilot and reversing valves so as to cut off exhaust of fluid from said cylinder thereby to stop the table, connections between said pilot and reversing valves thereafter being arranged to admit fluid to one of said end chambers first at a slow rate and then rapidly to shift the reversing valve into a reverse position, balanced springs normally to maintain said pilot valve in a central position, and passages between the end chambers and pilot valve which are interconnected when the pilot valve is in a central position to facilitate manual actuation of the reversing valve.

4. In a grinding machine having a reciprocable table, a piston and cylinder to reciprocate said table, a reversing valve therefor, end chambers in the opposite ends of said valve, a pilot valve for controlling the shifting of the reversing valve, a start and stop valve to control the exhaust of fluid from said cylinder, a table-actuated lever mechanism to shift both the pilot and reversing valves so as to cut off exhaust of fluid from said cylinder thereby to stop the table, fluid connections between said pilot and reversing valves thereafter being arranged to admit fluid to one of said chambers first at a slow rate and then rapidly to shift the reversing valve into a reverse position, means normally to maintain the pilot valve in a central position, and passages between the end chambers and pilot valve which are interconnected when the pilot valve is in a central position, said latter passages being arranged to facilitate exhaust of fluid from the inactive end chamber when the pilot valve is shifted from a central position.

5. In a grinding machine having a reciprocable

table, a piston and cylinder to reciprocate said table, a reversing valve therefor, end chambers in opposite ends of said valve, a pilot valve, a stop and start valve to control the exhaust of fluid from said cylinder, a lever mechanism to shift both the pilot and reversing valves so as to cut-off exhaust of fluid from said cylinder thereby to stop the table, fluid connections between said pilot and reversing valves thereafter being arranged to admit fluid to one of said end chambers first at a slow rate and then rapidly to shift the reversing valve into a reverse position, means normally to maintain the pilot valve in a central position, passages between the end chambers and pilot valve which are interconnected when the pilot valve is in a central position, and lost motion connections in said lever mechanism to facilitate movement of the pilot valve to a central position after a table reversal has been completed.

6. In a grinding machine having a reciprocable table, a piston and cylinder to reciprocate said table, a reversing valve therefor, a manually operable lever to shift said valve, end chambers in each end of said valve, a pilot valve to control the admission to an exhaust of fluid from said end chambers, a reversing lever to actuate said pilot and reversing valves to stop said table, adjustable dogs on said table to actuate said lever, independent passages between the pilot valve and each of said end chambers, independent throttle valves in each of said passages to facilitate a slow initial shifting of the reversing valve when the table has been stopped, and independent ports in the reversing valve to by-pass fluid around the throttle valves after a predetermined slow shifting movement of the reversing valve rapidly and positively to complete the movement of the reversing valve, said passages being arranged when the pilot valve is in a central position to interconnect said end chambers to facilitate manual actuation of the reversing valve.

7. In a grinding machine having a reciprocable work table, a piston and cylinder to reciprocate said table, a reversing valve therefor, a pilot valve for controlling the shifting of said reversing valve, a start and stop valve to control the exhaust of fluid from said cylinder to facilitate starting and stopping table reciprocation, a manually operable table traverse mechanism including a normally engaged clutch, a cam on said start and stop valve, and a slidably mounted plunger actuated by said cam to disengage said clutch when the start and stop valve is shifted to a start position to render the manually operable traverse mechanism inoperative during hydraulic reciprocation of the table.

8. In a grinding machine having a reciprocable table, a piston and cylinder to reciprocate said table, a reversing valve therefor, a pilot valve for controlling the shifting of said reversing valve, a start and stop valve to control the exhaust of fluid from said cylinder to facilitate starting and stopping table reciprocation, a manually operable table traverse mechanism including a clutch, a spring normally to maintain said clutch in an engaged position, and a cam on said valve to facilitate releasing said spring so as to engage the clutch and thereby to render the manually operable traverse mechanism operative when the start and stop valve is moved to a stop position.

9. In a grinding machine having a longitudinally reciprocable table, a piston and cylinder to

reciprocate said table, a reversing valve therefor, a transversely movable wheel slide, a rotatable grinding wheel thereon, a wheel feeding mechanism including a fluid motor, a control valve therefor, operative connections between said valve and the table reversing valve whereby said control valve is actuated in timed relation with the table reversing valve to impart a feeding movement to the grinding wheel during table reversal, and a slidably mounted sleeve in said control valve which is moved longitudinally during shifting of the control valve to reset the timing of said valve ahead of dead center so that the infeeding movement of the grinding wheel is completed before the table starts movement in the reverse direction.

10. In a grinding machine having a longitudinally reciprocable table, a piston and cylinder to reciprocate said table, a reversing valve therefor, a transversely movable wheel slide, a rotatable grinding wheel thereon, a reversing valve for the feed motor including a slidably mounted valve stem having a plurality of integrally formed pistons, a slidably mounted sleeve surrounding said stem and pistons, a friction plunger normally to hold said sleeve against longitudinal movement, a plurality of ports in said sleeve to admit fluid to and exhaust fluid from the motor chambers, and projections on said valve stem which are arranged to engage and shift said sleeve longitudinally during reversal of said control valve to facilitate advancing actuation of the infeeding movement so that the infeed is completed during dwell at table reversal before the table starts movement in the reverse direction.

11. In a grinding machine having a reciprocable table, a piston and cylinder to reciprocate said table, a reversing valve therefor, a pilot valve for controlling the shifting of the reversing valve, a rotatable grinding wheel, a transversely movable slide therefor, a feeding mechanism for said slide including a fluid motor, a reversing valve therefor, operative connections between the table reversing valve and the motor reversing valve whereby the latter valve is actuated by and in timed relation with the table reversing valve to impart an infeeding movement of the grinding wheel during table reversal, bleeder pipes connecting opposite ends of table cylinder with the motor reversing valve, and separate ports in said valve which are arranged so that the pressure end of the table cylinder is automatically and continuously bled.

12. In a grinding machine having a reciprocable table, a piston and cylinder to reciprocate said table, a reversing valve therefor, a pilot valve for controlling the shifting of the reversing valve, a rotatable grinding wheel, a transversely movable slide therefor, a feeding mechanism for said slide including a fluid motor, a reversing valve therefor, operative connections between the table reversing valve and the motor reversing valve whereby the latter valve is actuated by and in timed relation with the table reversing valve to impart an infeeding movement of the grinding wheel during table reversal, bleeder pipes connecting opposite ends of the table cylinder with the vane motor reversing valve, separate ports in said valve, and chambers in said valve which are opened to the atmosphere so that the pressure end of the table cylinder is automatically and continuously bled.

13. In a grinding machine having a transversely movable rotatable grinding wheel, a reciprocable table, a piston and cylinder to reciprocate

said table, a reversing valve therefor, a pilot valve for controlling the shifting of the reversing valve, a bleeder control valve for controlling bleeding fluid from opposite ends of said cylinder, bleeder pipes connecting opposite ends of the table cylinder with said valve, separate ports in said bleeder control valve and operative connections between the table reversing valve and the bleeder control valve whereby the latter valve is actuated by and in timed relation with the reversing valve to render one or the other of said ports operative so that the pressure end of the table cylinder is automatically and continuously bled through one of said ports.

WALLACE H. WOOD.
